(57) **CLAIM**

The ornamental design for a lamp, as shown and described.

DESCRIPTION

FIG. 1 is a perspective view of a lamp showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an end view taken along line 8-8 in FIG. 2;

FIG. 9 is an exploded view thereof;

FIG. 10 is a top perspective of the upper cover thereof with the detail lines visible behind the transparent surfaces omitted for clarity of illustration;

FIG. 11 is a bottom perspective of the upper cover thereof with the detail lines visible behind the transparent surfaces omitted for clarity of illustration;

FIG. 12 is a top perspective of the side casing thereof with the detail lines visible behind the transparent surfaces omitted for clarity of illustration;

FIG. 13 is a bottom perspective of the side casing thereof with the detail lines visible behind the transparent surfaces omitted for clarity of illustration;

FIG. 14 is an enlarged view of an indicated portion in FIG.

12; and,

FIG. 15 is an enlarged view of another indicated portion in FIG. 12.

The dashed broken lines in the drawings illustrate a portion of the lamp and form no part of the claimed design. The upper cover and the side casing of the lamp are transparent.
